(57) **CLAIM**

The ornamental design for an artificial Christmas tree, as shown and described.

DESCRIPTION

FIG. 1 is a top perspective view of an artificial Christmas tree showing our new design;

FIG. 2 is a bottom perspective view thereof;

FIG. 3 is a front side elevation view thereof;

FIG. 4 is a right side elevation view thereof;

FIG. 5 is a rear side elevation view thereof;

FIG. 6 is a left side elevation view thereof;

FIG. 7 is a top plan view thereof; and,

FIG. 8 is a bottom plan view thereof.

The broken lines showing structural portions of the artificial Christmas tree are included for the purpose of illustrating environment and form no part of the claimed design.

1 Claim, 8 Drawing Sheets
